UNITED STATES PATENT OFFICE.

ALFRED W. HOUCHEIN AND CHARLES E. LUBURG, OF KIRKWOOD, NEW JERSEY,
ASSIGNORS TO SHOCKLESS ELECTRIC CORPORATION, OF KIRKWOOD, NEW
JERSEY, A CORPORATION OF NEW JERSEY.

COIL.

1,306,815.

Specification of Letters Patent. Patented June 17, 1919.

Application filed April 30, 1917. Serial No. 165,592.

To all whom it may concern:

Be it known that we, ALFRED W. HOUCHEIN and CHARLES E. LUBURG, citizens of the United States, residing at Kirkwood, in the county of Camden and State of New Jersey, have invented certain new and useful Improvements in Coils; and we do declare the following to be a full, clear, and exact description of the invention, such as will enable others skilled in the art to which it appertains to make and use the same.

This invention relates generally to electrical appliances, but more particularly to an electro-magnet of improved construction.

One object of the invention is to provide a principle of magnet construction which may be effectively and practically employed as a spark coil for ignition systems, as a field magnet for dynamos or other current generating machines and devices, and is applicable for many other uses too numerous to herein enumerate.

Another object of the invention is to generally improve upon devices of this character by the provision of a comparatively simple, strong, durable and inexpensive construction, and one which will be efficient and reliable in operation, and well adapted for the purposes for which it is designed.

With these and other objects in view, the invention resides in certain novel features of construction, and the combination and arrangement of parts to be hereinafter fully described and claimed.

The descriptive matter of the application is supplemented by the accompanying drawings in which—

Figure 1 is a diagrammatic embodiment of the principle of the invention, illustrating its use as a spark coil in connection with a make and break ignition system for internal combustion engines;

Fig. 2 is an end view of the spark coil or electro-magnet according to this present embodiment of the invention;

Fig. 3 is a central vertical longitudinal sectional view of the electro-magnet;

Fig. 4 is a transverse sectional view thereof taken on the plane indicated by the

line 4—4 of Fig. 3 and looking in the direction of the arrows;

50

Fig. 5 is an enlarged detail central vertical longitudinal sectional view of a portion of the electro-magnet;

Fig. 6 is a diagrammatic central vertical longitudinal sectional view of a simplified 55 form of electro-magnet;

Fig. 7 is a diagrammatic embodiment of the principle of the invention, illustrating its use as a field magnet for a dynamo, showing also diagrammatically a line circuit for 60 the dynamo and the necessary appurtenances therein;

Fig. 8 is a vertical transverse sectional view of the dynamo, such view being taken on the plane passing through the central 65 axis of the core of the field magnet thereof;

Fig. 9 is an enlarged vertical sectional view of a portion of the field magnet of the dynamo;

Fig. 10 is a transverse sectional view, 70 partly broken away, of the core of the field magnet coil of the dynamo;

Fig. 11 is a side elevation, partly broken away and in section, of a modified form of conductor which may be used for winding 75 of the coil, in whatever manner it is to be used;

Figs. 12, 13 and 14 are similar views of further modifications of the conductor for the winding of the coil; and

80

Figs. 11^a, 12^a, 13^a, and 14^a are transverse sectional views of the conductors above referred to, taken respectively on the planes of the lines 11^a—11^a, 12^a—12^a, 13^a—13^a, and 14^a—14^a of Figs. 11, 12, 13 and 14 respectively.

In specifically describing the structure shown in the drawings above briefly described, characters will be placed on the numerous elements, and reference will be 90 herein made to them by their respective indices. To this end, referring for the present to Figs. 1 to 5, the numeral 1 designates a core, which may be formed in any suitable manner, but which is preferably 95 made up of a plurality of soft iron wires 2 made into a bundle, and here shown as being

circular in cross section. Extending through a central longitudinal opening 3 in the core 1 is a current conducting member or rod 4, composed preferably of copper. This 5 per rod 4 preferably contacts with the innermost iron wires 2 throughout the entire length of the latter, and has its ends projecting beyond the ends of the same for a purpose which will hereinafter appear.

10 The opposite ends of the core 1 are wedged into the central openings 5 and 6 of a pair of plates 7 and 8 respectively, it, however, is to be understood that any other suitable means may be utilized for accomplishing this mounting. These plates 7 and 15 8 serve as heads for the coil for supporting the same and for retaining the winding thereon.

The winding just referred to is designated 20 by the numeral 9. It is composed of separate and independent sections 10 and 11 of copper and iron wire respectively, the cross sectional area of the copper wire being slightly greater than that of the iron wire, 25 as most clearly shown in Fig. 5 of the drawings. However, it is to be understood that the relative sizes of the iron and copper wires may be changed to produce the best results according to the manner in which the 30 electro-magnet is to be used.

The winding 9 is wound upon the core in any desired number of layers, the sections 10 and 11 being wound at the same time and being disposed side by side. Between the 35 adjacent layers of winding and between the inner layer thereof and the core 1 are disposed strips 12 of paper or other suitable wrapping to form a smooth support for the wires in winding the same.

40 The inner ends of the sections 10 and 11 are electrically connected with the copper rod 4 and incidentally with the iron core 1, inasmuch as the wires 2 of which the latter is composed are in contact with said rod. 45 While this connection may be made in numerous ways, the most convenient is by wrapping or winding these ends of the sections around one of the protruding ends of the copper rod 4 as shown at 13, and then 50 soldering them thereto.

The other or outer end of the iron section 11 is wrapped or wound around and soldered to the other protruding end of the rod 4, and thus similarly electrically connected 55 with the latter and with the core 1. This end of the rod 4 is electrically connected with a binding post 16 by a short conductor 17, said binding post being fixed to the coil head 7 in any suitable manner. Fixed to the 60 head 7 in a similar manner is a second binding post 18 to which the other or outer end of the copper section 10 is electrically connected. It is to be here understood that the provision and location of the binding posts 65 16 and 18 is merely a matter of convenience,

and forms no part of the present invention, and may be entirely omitted, moved to another position, or other suitable devices substituted therefor as occasion requires.

Fig. 6 illustrates a modified and simplified 70 form of the electro-magnet. From this it may be seen that the copper rod 4 has been entirely omitted, and also that the ends of the iron section 11 are left free, that is, they are not connected in any manner to the copper section 10 or the iron core 1. This simplified form of our electro-magnet will operate, but better results are obtained with the construction shown in Figs. 1 to 5.

In Fig. 1 of the drawings, the electro-magnet is diagrammatically represented, and is shown connected and arranged in the circuit of an ordinary make and break ignition system for internal combustion engines. In this figure, the letter B designates a battery, A an intermittently operable contact carrying arm, C a fixed contact, and D a circuit wire. The ends of the wire D are connected to the binding posts 16 and 18.

The electrical theories involved during the 90 operation of this electro-magnet as a spark coil, and the manner in which one element affects the others are not known, but extensive experimentation has shown that a hotter and larger spark is obtained with this coil 95 than with one of the ordinary construction using the same initial voltage. As far as can be determined, the electrical energy produced by the coil is shockless, for the bare wires or terminals of the coil can be readily 100 handled, and no current will manifest itself as being present therein except by the heat and spark at the time of the make and break. Thus, the coil is especially adapted for use by careless persons, and those who have very 105 little knowledge of and fear electricity.

Absolutely no waterproofing or impregnating insulation or varnish is necessary for application to the wire or wires which constitute the winding of this coil, and it is 110 therefore preferable to use an ordinary cotton covering for the copper wire with absolutely no waterproofing, insulating or impregnating agency. Obviously, the expense of manufacturing electro-magnets is greatly 115 reduced by this invention, for the windings heretofore known have necessarily been treated with some waterproofing or impregnating agency. Even with the ordinary cotton covering for the copper wire, the coil 120 will effectively operate when completely submerged in water. Furthermore, the spark can be produced under water.

Figs. 8, 9 and 10 illustrate the structural adaptation of this electro-magnet for use as 12 a field magnet for dynamo electric or other current generating machines and devices. In these figures, the letters E and F represent the pole pieces and G the armature of the well known type of dynamo. The pole 13

pieces E and F are detachably connected to the ends of a comparatively large, cylindrical soft steel core member 19 having therein a centrally arranged longitudinally extending opening 20. Disposed in this opening 20 is a supplemental core 21 composed, as in the spark coil, of a bundle of soft iron wires 22. Through the core 21 extends a copper rod 23.

Surrounding the portion of the member 19 which is disposed between the inner sides of the pole pieces E and F is a cylindrical or tubular spool member 24 provided at its ends with heads 25. The field winding, composed of sections 26 and 27 of copper and iron wire, is wound upon the spool member 24 in the same manner as the spark coil was wound, the sections being wound at the same time and being disposed side by side and connected with the copper rod 23 also in the manner above described.

Referring now to Fig. 7 of the drawings, where the dynamo is diagrammatically represented, it will be seen that the free end of the copper section 26 is connected by a conductor *a* to one terminal of a switch *b*, while the end of the copper rod 23 opposite to that to which the other end of the copper section 26 is connected, is connected by a conductor *c* to one terminal of a rheostat *d*, the other terminal of which is connected by a conductor *e* to the other terminal of the switch *b*. Conductors *f* and *g* connect the terminals of the switch *b* with the brushes *h* and *i* respectively of the dynamo. *j* represents the line circuit supplied by the dynamo and consists in the present instance of a plurality of incandescent lamps.

It has been found that the presence of a field magnet wound and connected in this manner causes an instantaneous and automatic regulation when the load is suddenly increased or decreased about 25%. If a short circuit is effected across the switch *b*, a complete demagnetization of the field magnet takes place. As soon as the short circuit is removed, the voltage at once resumes its normal amount.

Where the increase or decrease in the load is 25% or less, the regulation is so effective and instantaneous that no flickering of the lights in the circuit *j* is noticeable.

As is true in regard to the spark coil, moisture or water does not affect the operation of the field coil. It is therefore preferable to cover the copper section 26 merely with ordinary cotton wrapping without varnish or other impregnating agency.

In Figs. 11 and 11^a of the drawings, a modified form of the conductor for the winding of the coil, in whatever manner it is to be used, is shown. Here the two sections 28 and 29 are twisted together and covered with a single cotton wrapping 30.

Another modification of the above re-

ferred to conductor is shown in Figs. 12 and 12^a. In this, a plurality of copper and iron wires 28' and 29' respectively are twisted together the same as the strands of a rope or cable, and then covered with a single cotton 70 wrapping 30'.

In Figs. 13 and 13^a the copper and iron sections 28^a and 29^a are in the form of strips or ribbons disposed side by side and soldered or welded together, and then wrapped with 75 a single cotton covering 30^a.

A still further modification is shown in Figs. 14 and 14^a consisting of cotton covered, copper clad iron wire, the copper section being represented by the numeral 28^b, 80 the iron section by the numeral 29^b, and the cotton covering by the numeral 30^b. The specific construction of a coil constructed in accordance with this invention and using a conductor of this character, forms the subject matter of our co-pending application, Filed April 30, 1917, Serial No. 165,593.

While copper and iron are the preferred substances from which to construct the sections of the winding for the coil, yet numerous other substances may be substituted for them, so long as the copper substitute is a non-magnetic metal and the iron substitute is a magnetic metal.

In the claims where the current conducting member is defined as being "arranged in inductive relation with respect to one of said sections", it is not intended to necessarily be limited to disposing the conducting member within the winding of the coil. 100 Similarly, where it is defined as being "arranged in juxtaposition" with the core, it is not intended to be necessarily limited to extend through the core.

Numerous changes and modifications other than those herein enumerated may be made without departing from the spirit and principle of the invention as now claimed:

1. An electro-magnet including a winding composed of sections of magnetic and non-magnetic metals and a current conducting member connected in series with one of said sections and arranged in inductive relation with respect thereto.

2. An electro-magnet comprising a core, a current conducting member arranged in juxtaposition with said core, and a single winding for said core composed of sections of magnetic and non-magnetic metals, one of said sections being connected in series with 120 said current conducting member.

3. An electro-magnet comprising a core, a current conducting member extending longitudinally through said core, and a single winding for said core composed of sections 125 of magnetic and non-magnetic metals, one of said sections being connected in series with said current conducting member.

4. An electro-magnet comprising a core, and a single winding for said core composed 130

- of sections of magnetic and non-magnetic metals, one of said sections having its terminals electrically connected with said core, another of said sections being adapted to be included in an electric circuit. 5
5. An electro-magnet comprising a core, a current conducting member arranged in juxtaposition with said core and extending longitudinally of the same, and a single winding for said core composed of sections of magnetic and non-magnetic metals, one of said sections being connected in series with said current conducting member, and another of said sections having its terminals electrically connected with said core and said current conducting member. 10
6. An electro-magnet comprising a core, a current conducting member arranged in juxtaposition with said core, said core and said member being composed respectively of magnetic and non-magnetic substances, and a single winding for said core composed of sections of magnetic and non-magnetic substances, one of said sections being connected 15
- in series with said current conducting member. 25
7. In an electromagnet, a core composed of a bundle of soft iron wires, a copper rod parallel with said soft iron wires and extending centrally through said core, copper wire wound around said bundle of iron wires and copper rod and having ends electrically connected respectively with the end portions of said copper rod and having other ends connected with a source of electric energy, and an iron wire wound around said bundle of iron wires and having its ends electrically connected to and terminating at the end portions of said copper rod beyond the ends of said bundle of iron wires. 30 35 40

In testimony whereof we have hereunto set our hands in the presence of two subscribing witnesses.
